UNITED STATES PATENT OFFICE.

ALLEN F. BECK, OF COLUMBUS, OHIO, ASSIGNOR TO THE CLARK GRAVE VAULT COMPANY, OF COLUMBUS, OHIO, A CORPORATION OF OHIO.

HANDLE CONSTRUCTION FOR GRAVE VAULTS.

Application filed March 23, 1927. Serial No. 177,728.

This invention relates to improvements in handle constructions adapted for use in effecting the support for transportation and general handling of metallic grave vaults. 5 A primary object of the invention resides in the provision of a handle structure for use in connection with grave vaults of strong construction, easy and convenient to apply in its operative position and in such 10 form as to present a pleasing and ornamental appearance.

Another object of the invention resides in the provision of a handle construction which is secured to and mounted on the outer walls 15 of a grave vault hood in such a manner as to avoid penetrating the wall of the hood with fastening appliances or in making openings of any kind therein which would be apt to affect the vault detrimentally following interment and thereby interfering with the fluid seal normally provided thereby.

With these and other objects in view, as will appear as the description proceeds, the 25 invention consists in the novel features of construction, combinations of elements and arrangements of parts hereinafter to be fully described and pointed out in the appended claims.

30 In the accompanying drawing:

Figure 1 is a side elevation of a grave vault provided with the improved handle structure comprising the present invention.

Figure 2 is a similar view on an enlarged 35 scale disclosing in greater detail the construction of the handle structure,

Figure 3 is a horizontal sectional view on the line 3—3 of Figure 2,

Figure 4 is a vertical transverse sectional 40 view on the line 4—4 of Figure 2.

Referring more particularly to the drawings the numeral 1 designates a sheet metal grave vault which is formed to comprise the usual base 2 and open bottom hood section 3, the latter being formed to comprise the usual vertical side and end walls and a crown top, the lower edges of the hood sections resting upon the base 2 in the usual manner when the sections of the vault are 45 assembled, as shown in Figure 1.

The improved handle construction comprising the present invention, is applied to the vertical side and end walls of the hood section and is formed to comprise a plurality of fixed horizontally extending studs 55

4. These studs are formed to comprise enlarged heads 5, which engage flatly with the outer surfaces of the vertical walls of the hood and are permanently and securely associated therewith by a welding, fusion or 60 heat treating process, the arrangement permitting the studs to be applied directly to the outer surfaces of the hood walls, and avoids the formation of openings in the latter which might interfere with the sealing of the vault.

Surrounding each of the studs and applied to the outer surfaces of the vault are sheet metal casings 6, which are of substantially rectangular form and include front 70 and side walls and open sash. The front walls are apertured as at 7 for the reception of the protruding shanks of the studs 4, and the outer ends of the studs are threaded for the reception of nuts 8 by 75 which the casings are firmly secured to the sides of the vault, although, if desired, the casings too may be welded to the vault sides.

Certain of the side walls of the casing 6 80 are formed with slots 9 for the reception of the inwardly bent ends 10 of a plurality of strap links 11. The ends 10 lie within the confines of the casing 6 and are provided with openings for the reception of 85 the studs 4. The intermediate portions of the links lie between the associated casings 6 and are spaced horizontally from the adjoining sides of the vault 1 whereby during interment straps or the like may be associated with the links for the raising or 90 lowering of the vault.

Confined within the casing 6 in substantially horizontal positions are a plurality of pivot bolts 12 with which are connected 95 swinging and normally depending hinged straps 13. To the depending ends of these straps there is secured as at 14 a plurality of depending handle supporting members 15, which are preferably formed from metal 100 and include adjoining side portions between which the straps 13 are positioned, the bolts 14 serving to securely connect the adjoining side portions of the members 15 with said straps. The extreme lower ends of the 105 members 15 are widened and shaped to receive and grip a hollow longitudinally extending metallic handle bar 16, which extends longitudinally along each of the sides of the vault and also along the ends thereof. 110

The construction thus described provides a simple, substantial and pleasingly designed handle construction for use especially in connection with grave vaults, and more particularly a construction which admits of the securing thereof directly to the sides of the vault without penetrating the walls of the latter. The upper ends of the members 15 may be provided with outwardly turned shoulders 17 which engage with the outer walls of the casing 6 when the handle bar is raised to a supporting position, shown by dotted lines in Figure 3, the shoulder 17 maintaining the bars 16 in a horizontal position properly spaced from the sides of the vault so as to be readily gripped for supporting purposes. The straps 13 are movable in openings 18 provided in the front walls of the casing below the aperture 7, so that free swinging movement on the part of the straps may be secured. The base 2 may also be provided with fixed handle members 19 but which do not enter into the present invention. In cross-section the handle bars 16 are substantially square and the members 15 are shaped accordingly so as to prevent rotation of said bars in their supports. The various parts of the handle construction may be formed from stamped sheet metal and thus economically produced and at the same time an attractive appearance presented.

What is claimed is:

1. A handle construction for grave vaults embodying a pair of spaced studs integrally secured to the vertical side walls of a vault, a pair of casings applied to said wall and formed with openings in the front thereof for the reception of said studs, members carried by the outer ends of said studs for retaining said casing in their applied positions, a strap link arranged between said casings and having the opposite ends thereof

passed through openings in the sides of said casings, the ends of said links being apertured to receive the studs, and pivoted handle members connected with the casing. 45

2. A handle construction for grave vaults embodying a pair of spaced studs projecting horizontally from the side of a grave vault, 50 a pair of casings apertured to receive said studs, binding nuts carried by the outer ends of said studs for retaining said casings in their applied positions, a strap link having offset ends arranged to pass through openings provided in the sides of said casings, the ends of said links being provided with openings for the reception of said studs, and a pivoted handle member depending from 55 said casing. 60

3. A handle construction for grave vaults, embodying a pair of spaced casings directly secured to the outer walls of a vault, horizontally positioned bolts located within said casings, a pair of swinging straps carried 65 by said bolts, a longitudinally extending handle bar, and a plurality of sheet metal supporting members surrounding said bar and having their upper ends spaced to receive said straps to which said members are 70 secured.

4. A handle construction for grave vaults embodying a pair of spaced casings directly secured to the exterior surfaces of a vault, hinged bolts arranged in said casings, 75 depending tongues carried by said bolts, a handle bar, and a pair of straps arranged to receive said handle bar and having the upper ends thereof spaced to receive said tongues, securing means passing through 80 said straps and tongues, and shoulders provided in connection with said straps and engageable with said casing to limit the upward swinging movement of said handle bar.

In testimony whereof I affix my signature.
ALLEN F. BECK.
